UNITED STATES PATENT OFFICE.

TONJES AUGUST CARL BOTH, OF MALDEN, MASSACHUSETTS, ASSIGNOR TO THE ZEE SOCKET AND MFG. CO., OF BOSTON, MASSACHUSETTS, A CORPORATION OF MASSACHUSETTS.

ELECTRIC-LIGHT SOCKET.

1,175,590.

Specification of Letters Patent. Patented Mar. 14, 1916.

Application filed March 29, 1912. Serial No. 687,179.

To all whom it may concern:

Be it known that I, TONJES AUGUST CARL BOTH, a citizen of the United States, and a resident of Malden, in the county of 5 Middlesex and State of Massachusetts, have invented certain new and useful Improvements in Electric-Light Sockets, of which the following is a specification, taken in connection with the accompanying drawings, which form a part of the same.

My invention relates to electric light sockets, regardless of any particular switch mechanism.

It further relates to certain details of construction of the electric light socket which will be more fully hereinafter described in the specification and pointed out in the claims.

I have shown a switch mechanism in an 20 electric light socket to which it is particularly adapted owing to its simplicity, the few parts, and the small space occupied by them. When so used it makes a quick make and a quick break of the electric current, without arcing, upon the rotation of the driving member in either direction. I have furthermore shown my electric light socket equipped with my improved switch mechanism, but, it is, of course, to be distinctly understood that any form of switch mechanism may be used in the socket, for 30 my invention, as to the socket, is not to be limited in any particular by the mechanical movement shown, though I preferably 35 though not necessarily use the mechanical movement shown as the switch mechanism.

In the accompanying drawings, showing 40 illustrative embodiments of my invention and in which the same reference numerals refer to similar parts in the several figures—Figure 1 is a side elevation of my electric light socket, the shell and cap being shown in section for purposes of clearer illustration. To show one of the marked 45 advantages of my electric light socket, I have, for convenience in description, shown also in Fig. 1 a husk in section with which my electric light socket is particularly adapted to be used: Fig. 2 is a longitudinal 50 vertical section substantially on the line 2—2 of Fig. 1, looking in the direction of the arrow; Fig. 3 is a transverse horizontal section substantially on the line 3—3 of Fig. 1 looking in the direction of the 55 arrows: Fig. 4 is a plan view of the insulat-

ing member shown in Fig. 2; Fig. 5 is a detail plan view of the resilient driven member; Fig. 6 is a detail plan view of the blank from which the driving member is formed; Fig. 7 is a face view of the hill and valley member carried in any suitable manner by the driving member; Fig. 8 is a side elevation of one of the insulating members, looking in the direction of the arrow marked 8 in Fig. 3; Fig. 9 is a side elevation of a modification, a part of the structure being shown in section and part broken away for purposes of clearer illustration; Fig. 10 is a detail sectional view on an enlarged scale, showing the preferred means for rotatively 70 connecting the shell to the cap; Fig. 11 is a perspective view of the preferred form of positioning member when such a member is carried by the cap rather than by the nipple or similar member; Fig. 12 is a detail 75 fragmentary side elevation, partly broken away, showing one means of connecting the screw shell, or other holder for a consuming device of Fig. 9 to the insulating member which is usually porcelain; Fig. 13 is a plan 80 view of the screw shell shown in Fig. 14; Fig. 14 is a side elevation, partly broken away, of the screw shell illustrated in Figs. 9, 12 and 13; and Fig. 15 is a detail fragmentary section of a modified form of positioning means.

In the illustrative embodiments of my invention shown in the drawings, 1 is a cap of my electric light socket, which partly protects the insulating member 3 when the parts are assembled, Figs. 1 and 2. This insulating member may be formed in various ways. Preferably, I form it out of a plurality of coöperating insulating members, preferably 90 two, 4 and 5, which have their meeting surfaces 6, 6 extending substantially longitudinally of the electric light socket, though my invention is not to be confined to the number of members. In the head of the insulating member 3, I provide engaging members 8, 8, one or more such engaging members may be used but preferably I use more than one such engaging member, as for example, four of them as shown in Fig. 4 though it is to be understood that this number may be varied without departing from my invention. These engaging members I 95 preferably, though not necessarily, form on the insulating member 3, usually though not necessarily, as indentations in the porcelain, 100 105 110 115

though it is to be understood that my invention is not to be limited to this form or this manner of providing the insulating member 3 with surfaces to coöperate with the coöperating member. This coöperating member may be formed of various shapes and contours and be formed either as a separate member as, for example, 10 in Figs. 1, 9 and 11, or formed as 5 a part of the nipple 96, Fig. 15. It is provided with at least one surface to coöperate with the engaging members, whatever their form may be, carried by or formed in the insulating member 3. Preferably this 10 positioning member 10 is formed as a ring and provided with one or more fingers 11, 11, Fig. 11, to coöperate with the engaging surfaces carried by the insulating member 3, Figs. 1, 2, 3 and 9. I may, however, form the 15 lower end of the nipple 96 as a positioning member and provide it with one or more arms, lugs or teeth 97 to coöperate with the engaging members 8 carried by the insulating member 3.

20 The positioning member 10 is secured to the cap 1 in any suitable manner. In one form of my invention, the screw threaded nipple 12 is provided with a shoulder 13 against which is firmly and non-rotatably held both the cap 1 and the positioning member 10 by upsetting the end 14 of the 25 nipple.

30 In Fig. 9 I have shown the positioning member 10 secured to the cap 15 by bending 35 in a portion 16 of the cap 15 so as to firmly and non-rotatably hold the positioning member to the cap.

35 The cap 1 is also provided with any suitable coöperating surface, to coöperate with 40 a similar one carried by the shell 17 of the socket, the coöperating surfaces being such as to permit free relative rotation between the shell and cap, but which will not permit the shell to be disengaged from the cap by 45 an ordinary or light pull longitudinally of the socket. By way of example, I have shown the cap 1 provided with an interior channel or groove 18, Figs. 1 and 10, having the lip 19 over which is sprung a coöperating member carried by the shell 17. By 50 way of example, but to which my invention is not to be limited, I provide this shell 17 with one or more rivets or pins 20, preferably two, so that by compressing the shell 55 17 slightly, the pins or rivets 20 can be forced by the lip 19 of the groove, Fig. 10, when the resiliency of the shell 17 will assert itself and cause the pins or rivets 20 to become seated in the channel or groove 18 of the cap. While I have shown this arrangement as the preferred construction, it 60 is to be distinctly understood, of course, that any similar locking surfaces between the cap and shell which will permit the free rotation of the shell with relation to the cap 65

and prevent the disengagement of the two would come within the terms of my invention as defined by the claims.

70 It is now quite common to mount or install electric light sockets in members which serve to conceal very largely the socket and which are given various shapes and contours, many of which are extremely artistic. In the art these surrounded members are known as husks. It has been found in practice to be quite burdensome and to increase the cost of installation, particularly the labor item, to mount the sockets within these husks. That portion of my invention which relates to the electric light socket will 75 be advantageous even though the socket is not used with a husk, but it is particularly adapted for use with such husks whatever their shape or configuration may be. I have shown, therefore, for purposes of illustration a husk 21, Fig. 1, which is secured on the arm 22 of the fixture in any suitable manner, preferably by being held on the arm by screwing up the nipple 12 so that the 80 husk will be secured to the arm 22. In so securing the husk, the cap 1 and the positioning member 10 are separated from the rest of the socket. After the husk 21 and the cap 1 have been secured on the arm 22, the key 23 is then threaded through the 85 opening 24 of the husk. Then the upper portion of the shell 17 is slightly compressed so that the lugs or pins 20 are snapped over the lip 19 of the groove 18 of the cap. At the same time, one or more of the fingers 11 of the positioning member 10 and the engaging members 8 on the insulating member 3 will be brought into engagement, or if in 90 joining the parts they do not immediately engage, a slight rotation of the insulating member 3 will cause the fingers 11 to engage with the engaging members 8 carried by the insulating member and will then prevent further relative rotation between the insulating member 3 and the cap 1 in an obvious manner. The engagement of these fingers 11 with the coöperating members 8, 8 in the 95 insulating member will also at the same time prevent the relative rotation of the shell 17 with relation to the cap 1 either by the key 100 23 which extends through the slot 25 in the shell 17 or by the coöperating surfaces 67 and 68 to be hereinafter described. By the same means, the husk 21, if one is used, will 105 also be prevented from relative rotation in relation either to the support 22 or to the shell 17. It is, of course, to be understood that the lugs or teeth 97 on the end of the nipple Fig. 15 will perform the same function as the ring 10 with its arms 11, the lugs or teeth 97 coöperating with the engaging member or members 8 on the insulating member.

110 With my improved electric light socket, I avoid the necessity of using any insulation 115 120 125 130

within the cap 1 and thereby save the expense not only of the material of such insulation but of the labor of assembling it in the cap. In addition to the advantages of omitting the insulating lining in the cap above set forth, it is found in practice that the caps have to be replated after a certain interval of time varying in different localities and different uses to which the sockets are employed. On such replating the usual insulating lining is removed and in again assembling the socket, it is often omitted through carelessness or some such cause. When the replated socket and cap are attached together and reshipped or given out to the workmen, there is no means of telling whether or not such sockets are complete and ready for use without taking each cap off of each shell. In the prior constructions on the market the socket is incomplete without this lining in the cap and cannot be used. Consequently, when the lining of the cap is omitted, there are often expensive delays and loss of time until a complete socket is obtained or a new lining for the cap. With my invention, in which no lining is ever used, no such delays can occur. The usual insulation 26 in the shell 17 is employed.

My mechanical movement includes a rotary driving member 27 and a reciprocating resilient driven member 28. This driving member may be formed in various ways, though preferably I form it from a stamping, Fig. 6, having a head 29 and an arbor 30 which may be swaged or rounded in any suitable manner to form the arbor of the driving member 27. At the same time that the head is stamped or formed, I preferably, though not necessarily, provide it with a U-shaped slot 31, Fig. 6, forming a lip 32 and also provide it with inclined grooves 33, 34, Fig. 7, which have their lowest portions at 95, 95 and their highest portions at 35 and 36, which points are substantially in the same plane as the intermediate or central portion 37 of the head 29 which is substantially flat. The blank is bent back upon itself to form a crank 38 and so shaped as to leave the head 29 at an angle to the arbor 30 as shown in Fig. 3. While I preferably form the head crank and arbor integral, my invention is not to be confined to this construction.

The resilient driven member may be formed in various ways. Preferably I stamp it from sheet metal and bend it back upon itself at 39. The driven member at this point is preferably rounded or arched as shown in Fig. 5 to insure greater strength and resiliency. Of the two arms 40 and 41, Fig. 5, the latter, toward its end, is preferably cut away, the very end of the arm 41 being preferably, though not necessarily, bent at an angle to make a nose 42. This nose is the portion which directly co-operates

with the head 29 of the driving member 27. It normally rests on either the portion 35 or 36 of the inclined groove 33 and 34. By rotating the driving member 27 in either direction, this nose piece 42 will be caused to move up either the inclined groove 33 or 34, depending upon the direction of rotation of the arbor 27, until such time as the nose piece reaches the highest point of the two inclined grooves 33 and 34 which is on the surfaces 35 and 36. When the nose piece reaches the surfaces 35 and 36, it is no longer confined by the grooves 33 and 34 and will immediately with a quick and positive snap, fly back across the flat surface 37 to the opposite surface 35 or 36 as the case may be. This is true whichever groove 33 or 34 it takes to ascend to the points 35 and 36. In other words, the travel of the nose piece is always up one of the grooves 33 or 34 and always back to the surface 35 or 36, as the case may be, by way of the surface 37.

The crank 38 and the inclination of the head 29 serves to compress the resilient driven member 28 by forcing the nose piece 42 toward the arm 40 until such time as the rotation of the driving member brings the point 36 directly in contact with the nose piece 42 when the nose piece will instantly fly back to the position designated 35, Fig. 7, and in doing so it causes the entire resilient driven member 28 to move laterally with a quick and positive snap. I have so shown the mechanical movement in the drawing. An ordinary insulating key 23 is attached in any suitable manner to the driving member 27. When so used the resilient driven member 28 serves to make a quick make and a quick break of the electric current, without arcing, upon the rotation of the driving member in either direction.

The insulating member 3 of the electric light socket illustrated is, as previously noted, preferably formed of two complementary insulating sections 4 and 5. Each of these sections is provided with a meeting face 6, and a strain relief comprising the divergent and circuitous passages 43, 43 which meet at the bridge 44, which point serves to separate the two feed wires and cause them to follow their respective curved passages 43, 45 and 43, 45. Each pair of passages 43 and 45 join each other near the periphery of the insulating section 3. By making these curved passages 43 and 45 in the insulating members, I form a strain relief integral with the insulating portion of the socket, and one which transmits substantially all the strain which may be thrown upon the feed wires to the walls of the different circuitous passages. In wiring the socket one of the feed wires (not shown) is attached to the binding screw 46 on the binding plate 47, while the other feed wire (not shown) follows the other circuitous

4
passage 43, 45 and is connected to the binding post 48 carried by the binding plate 49.

Each of the insulating sections 4 and 5 is molded to form an interior chamber 50.

5 This chamber is extended through one of the insulating sections, as for example 4, to permit ready molding of the parts without cross holes and to permit the ready insertion of the resilient driven member 28.

10 I also preferably form a groove 51 in one of the walls of the recess 50 to permit the free rotation of the lip 32 of the head 29 of the driven member 27. Each of the insulating members 4 and 5 is also provided with 15 a semi-circular groove 52 to form a bearing for the arbor 30 of the driving member 27, and with a boss 53 near their lower ends to coöperate with and hold the screw shell or other holding device 54.

20 The upper end 55 of the screw shell is cut away to receive the bosses 53, 53 of the different insulating sections 4 and 5 which fit within the upper portion of the screw shell 54 and beneath the head 56 of the screw shell, Fig. 2. In assembling the two sections 25 4 and 5, these bosses 53, 53 are readily inserted from different sides through the cut out portions 55, 55. The screw shell is also provided with a contact member which ex-

30 tends up into the interior chamber 50. This contact member may be variously formed. Preferably I form it by cutting the head 56 of the screw shell so as to form an integral arm 57 which is bent up substantially at 35 right angles to the head 56 of the screw shell and forms one contact to coöperate with the resilient driven member 28 of the mechanical movement or switch mechanism. The other contact 58, Figs. 2 and 3, is also mounted 40 within the chamber 50 and separated from the shell contact 57. This contact 58 may be mounted in various ways. Preferably it is carried by a binding plate 47 on which is mounted the binding screw 46. I have 45 shown in the preferred construction the contact and binding plate formed of one integral piece of metal, though my invention is not to be confined to this structure. This binding plate 47 is held to the insulating 50 section 5, and the two sections 4 and 5, are at the same secured together, by the screw or other suitable securing means 61. The center contact 62 is mounted on the insulating section 3 in any suitable manner, such 55 as by the binding post 49 carrying the binding screw 48. This binding post 49 is secured to the insulating section 4 by means of the screw 63 as shown in dotted lines in Fig. 3, which screw also serves as an additional means to hold the two sections 4 and 60 5 together.

In wiring the socket, the two feed wires are forced down the throat 66 formed by the complementary openings in the two sections 65 4 and 5 until the feed wires are separated by

the bridge 44 when each wire will be threaded through its own circuitous channel 43 and 45, as previously described.

Upon rotating the driving member 27 by the insulating button 23 in either direction, 70 the resilient driven member 28, in the manner previously described at length, will be caused to reciprocate back and forth in the recess 50 with a quick snap to make a quick make and a quick break of the electrical current, 75 without arcing, by bridging the gap or interval between the two contacts 57 and 58.

To further prevent the relative rotation of the shell 17 and the insulating member or porcelain 3, I preferably provide the insulating section 3 with cut out portions 67, 67. I have shown these two surfaces 67, 67 cut out of the independent sections 4 and 5, respectively, though, of course, they could be otherwise located, without departing from 85 my invention. I then provide the socket shell 17 with some suitable engaging member or members to coöperate with the co-operating member carried by the insulating section 3. One form of coöperating members is the bent in ribs 68 of the socket shell which coöperate with the cut out portions 67 and will prevent the relative rotation of the socket shell with relation to the insulating section 3. By this arrangement, I not 90 only prevent the relative rotation of the socket shell and the insulating section 3 but prevent the socket shell from cutting into or otherwise marring the key 23 which is usually formed of some insulating material. 100 These coöoperating surfaces, however, between the socket shell and the insulating sections 3 may be omitted if desired, in which case the key 23 itself would prevent the relative rotation of the socket shell and the insulating section 3. 105

In some instances, I provide the different insulating sections with an integral throat 91, one half of the throat being mounted upon each of the sections 92, 92, Fig. 9. By this arrangement I avoid the necessity of using the ordinary insulating bushing, a portion of which extends in the ordinary socket through the top of the cap. The feed wires (not shown) are threaded through the throat 91 and are separated by the bridge 72, when they will follow their respective circuitous passages 43, 45, and be connected to their respective binding posts, as in the other form. In this form of my invention I use a somewhat different form of screw shell 79. This screw shell is cut away at 80 and 81, leaving the head of the screw shell formed of two cross bars 82 and 83. The lower end of the insulating sections 92, 92 are provided with lugs 84, 84 and 85, 85, the lugs 85, 85 being provided with slots 86, 86 and the lugs 84, 84 with slots 87, 87. The lugs 84 and 85 are duplicates, one lug 84 and one lug 85 being mounted on each section 92. In assem- 115 120 125 130

bling the insulating section, Fig. 9, and the screw shell 79, the respective cross bars 82 and 83 are caused to slide into their respective slots 86, 86 and 87, 87 by sliding the insulating member with relation to the screw shell transversely to the longitudinal axis of the socket, Figs. 9 and 12. To prevent the screw shell from sliding out of the slots 86, 86 and 87, 87, I use any suitable locking means to keep them in their assembled position. One such locking means is to provide one of the insulating sections with a groove or depression 89 within which is forced some of the metal of the cross bar 82 after the screw shell 79 has been assembled. This metal of the bar will then form a seat 90, Fig. 12, which will prevent any accidental or unintentional separation of the insulating section 7 and the screw shell 79.

Having thus described this invention in connection with the several illustrative embodiments thereof to the details of which I do not desire to be limited, what is claimed as new and what it is desired to secure by Letters Patent is set forth in the appended claims:

1. An electric light socket comprising contacts; a switch mechanism including an operating member rotatable about its longitudinal axis and provided with a single inclined operating surface and a sliding resilient member operated by said operating member to slide bodily at substantially right angles to the longitudinal axis of said operating member to bridge said contacts; and conductors electrically connected to said contacts.

2. An electric light socket comprising contacts; a switch mechanism including an operating member rotatable about its longitudinal axis and provided with a single inclined operating surface, and a sliding resilient member directly contacting with the rotary operating member and operated thereby to slide bodily at substantially right angles to the longitudinal axis of the rotary member so as to bridge said contacts; and conductors electrically connected to said contacts.

3. An electric light socket comprising contacts; a switch mechanism including a support, a rotary operating member provided with a single inclined operating surface, and a spring bent back on itself forming two arms, one of which directly co-operates with the single inclined operating surface and the other of which slides upon the support transversely to the longitudinal axis of the rotary operating member to bridge said contacts; and conductors electrically connected to said contacts.

4. An electric light socket comprising contacts; a switch mechanism including a rotary operating member provided with a bent portion and a single inclined surface carried by

the bent portion and a spring member directly co-operating with the single inclined operating surface and operated thereby to bridge said contacts; and conductors electrically connected to said contacts.

5. An electric light socket comprising contacts; a switch mechanism including an operating rotary member provided with a single inclined operating surface having one or more grooves in its face and a resilient member provided with a surface to co-operate with the groove or grooves during a portion of the rotation of the driving member, said resilient member being operated by said operating member to bridge said contacts; and conductors electrically connected to said contacts.

6. An electric light socket comprising contacts; a switch mechanism including a rotary operating member provided with a single inclined operating surface having two inclined grooves extending part way around the single operating surface of the operating member and a resilient member provided with a surface to co-operate with the inclined grooves, said resilient member being movable to bridge said contacts; and conductors electrically connected to said contacts.

7. An electric light socket comprising contacts and switch mechanism including an operating member provided with a bent portion and an inclined head carried by the bent portion, said head having a single operating surface for a spring driven member, and a spring driven member having a surface that directly co-operates with the single operating surface of the head, said driven member being movable to bridge said contacts; and conductors electrically connected to said contacts.

8. An electric light socket comprising contacts; a switch mechanism including a rotary operating member provided with a single inclined operating surface, a resilient member co-operating with the single inclined operating surface, and means to guide the resilient member so that it will move bodily at substantially right angles to the axis of the rotary member to bridge said contacts; and conductors electrically connected to said contacts.

9. An article of manufacture for an electric light socket comprising an integral switch operating member stamped from sheet metal and provided with an arbor and a single operating head mounted at an angle to the arbor and provided with one or more inclined grooves.

10. In electric light sockets the combination of a metallic unlined cap provided with one or more downwardly extending locking arms, a shell, an insulating body member mounted on and protruding from the top of the shell and extending adjacent to the

under surface of the cap and provided with one or more recesses to coöperate with the locking arm or arms of the cap.

11. In electric light sockets, the combination of a metallic unlined cap provided with one or more downwardly extending locking arms, a shell, an insulating body member mounted on and protruding from the top of the shell and extending adjacent to the under surface of the cap and provided with one or more recesses to coöperate with the locking arm or arms of the cap, and means to connect the cap and shell together and permit free rotation of the shell with relation to the cap.

12. In an electric light socket, the combination of a key, an insulating member provided with one or more cut out portions, a socket shell provided with a key slot, one or both of the edges of the key slot being bent in to engage with the cut out portion or portions on the insulating member to prevent relative rotation between the socket shell and insulating member and cutting or marring the key.

13. In electric light sockets, the combination of an uninsulated metallic cap, a metallic shell to coöperate with the cap and provided with the usual insulation, an insulating body member adapted to seat in the metallic shell and to protrude from the top of the shell nearly to the underside of the metallic cap to act as an insulation for the unlined cap, said insulating body member provided with tortuous passages for the feed wires.

14. In electric light sockets, the combination of two fixed spaced contacts, a ro-

tary driving member provided with an inclined head having a single operating surface, and a sliding resilient conducting member operated by the single operating surface of the head to bridge the gap between the two fixed spaced contacts on one of its sliding movements and to disconnect the fixed contacts on the other of its sliding movements to make a quick make or a quick break of the current upon the rotation of the driving member in either direction.

15. In an electric light socket, the combination of an insulating member provided with a plurality of spaced downwardly extending lugs extending at an angle to the longitudinal axis of the insulating member each spaced lug provided with grooves also extending at an angle to the longitudinal axis of the insulating member and a shell provided with a plurality of spaced portions to be received in the grooves of the spaced lugs.

16. In an electric light socket, the combination of an insulating member provided with a plurality of spaced downwardly extending lugs extending at an angle to the longitudinal axis of the insulating member each spaced lug provided with grooves also extending at an angle to the longitudinal axis of the insulating member and a shell provided with a plurality of spaced portions to be received in the grooves of the spaced lugs and additional means to lock the shell to the insulating member of the socket.
